(57) **CLAIM**

The ornamental design for a clamping band, as shown and described.

DESCRIPTION

FIG. 1 is a front view of a clamping band incorporating my new design, in a closed configuration.

FIG. 2 is a front view thereof in a first partially opened configuration.

FIG. 3 is a top view thereof in the closed configuration.

FIG. 4 is a left side view thereof in the closed configuration.

FIG. 5 is a top view thereof in the first partially opened configuration.

FIG. 6 is a left side view thereof in a first partially opened configuration.

FIG. 7 is a front view thereof in a second partially opened configuration.

FIG. 8 is a top view thereof of the second partially opened configuration; and,

FIG. 9 is a left side view thereof in the second partially opened configuration.

The broken lines in the figures depict portions of the clamping band that form no part of the claimed design.
